Des. 200,381
Patented Feb. 16, 1965

200,381

PORTABLE RADIOGRAPHIC EXPOSURE UNIT

Lawrence P. Feer, Cazenovia, N.Y., assignor to General
Motors Corporation, Detroit, Mich.

Original design application Sept. 26, 1963, Ser. No.
76,745. Divided and this application Aug. 3, 1964,
Ser. No. 81,149

Term of patent 14 years

(Cl. D83—1)

FIG. 1

FIG. 2

FIG. 3

FIG. 4

FIG. 1 is a perspective view of a portable radiographic exposure unit, showing my new design;

FIG. 2 is a side elevational view;

FIG. 3 is a front elevational view, as seen from line 3-3 of FIG. 2;

FIG. 4 is a rear elevational view, as seen from line 4-4 of FIG. 2;

FIG. 5 is a side elevational view, as seen from line 5-5 of FIG. 4;

FIG. 6 is a top plan view, as seen from line 6-6 of FIG. 3; and

FIG. 7 is a bottom plan view, as seen from line 7-7 of FIG. 3.

This application is a division of application Serial No. D-76,745, filed September 26, 1963.

I claim:

The ornamental design for a portable radiographic exposure unit, as shown and described.
